RAIL JOINT

Elmer Schuppner, Des Plaines, Ill., assignor of
one-half to D. V. O'Connell, Chicago, Ill.

Application November 26, 1937, Serial No. 176,729

3 Claims. (Cl. 238—244)

My invention relates to rail joints, and includes among its objects and advantages the provision of an improved splice bar shim.

In standard rail joints employing rigid splice bars for connecting abutting ends of rails, considerable wear occurs on the medial areas of the splice bars as well as on the rail heads and base flanges at such areas. In tracks carrying unidirectional traffic, the wear is more pronounced and localized in a higher degree. Not only does the rail head and base flange become worn at the medial areas of the splice bars, but the load supporting faces of the rail heads become worn adjacent their abutting ends. In unidirectional tracks the load carrying faces of the approached rail ends are subjected to considerable wear and require frequent "building up" to bring the lower rail end up to the level of the adjacent rail end. Such rail end restoration requires considerable time and labor. Thus, in unidirectional tracks one rail end in each joint is subjected to more wear than the abutting rail end, while additional wear occurs between the under face of that rail head and the splice bar and on the lower edge of the splice bar and the base plate of the adjacent rail. Therefore, an object of my invention is to provide a rail joint shim designed to co-operate with conventional splice bars in such a manner as to compensate for the localized wear on the upper edge of the splice bar and underneath one of the rail heads and on the bottom edge of the splice bar adjacent the base plate on the adjoining rail.

Another object is to provide a rail joint shim designed to bring the lower rail to the proper level with respect to the adjacent rail before building up the end of the excessively worn rail head.

Another object is to provide a rail joint shim designed to compensate wear between the splice bar and the rail and in which the shim is designed for co-operation with conventional rails and splice bars.

In the accompanying drawing:

Fig. 1 is an elevational view of a rail joint showing my invention applied thereto with the splice part broken away for the sake of clearness;

Fig. 2 is a sectional view along the line 2—2 of Fig. 1; and

Fig. 3 is a perspective view of the shim.

In the embodiment selected for illustration, the shim 10 comprises a metal plate 12 shaped to provide a flange 14 arranged to lie between the upper edge 16 of the splice bar 18 and underneath the surface 20 of the rail head 22. Diagonally opposite the flange 14 the plate 12 is shaped to provide a flange 24 arranged to lie between the

lower edge 26 of the splice bar 18 and against the surface 28 of the base flange 30 of an adjacent rail.

Plate 12 is in the nature of two plate areas 32 and 34 integrally connected with the flanges 14 and 24, respectively. Flange 14 and the plate area 32 taper outwardly to feather edges 36, while flange 24 and the plate area 34 taper outwardly to feather edges 38.

Figs. 1 and 2 illustrate conventional rail ends 10 and 40 and 42 connected by the splice bars 18 and bolts 44. Each rail joint includes two splice bars and two shims 10 of identical construction so that the description of one side will apply to both. In connection with Fig. 1, assuming that the traffic is unidirectional as indicated by the arrow 46, the rail end 42 immediately adjacent the rail end 40 is subjected to considerable wear on the load carrying face of its head 22. In time, the rail end 42 becomes worn to such a degree as to require a building up. In unidirectional trackage considerable wear occurs between the upper edges of the splice bars 18 and the faces 20 of the rails 42. Such wear is at its maximum at the end of the rail and tapers gradually inwardly thereof. In most cases very little if any wear occurs between the upper edges of the splice bars 18 at their ends or on the faces 20 at such areas. At the same time, the lower edges of the splice bars 18 wear excessively adjacent the faces 28 on the rail ends 40. The faces 28 also become worn, but this wear and the wear on the lower edges of the splice bars 18 is at its maximum adjacent the rail end 42 and tapers inwardly of the rail ends 40 and outwardly of the splice bars.

To compensate such distribution of wear, I place a shim 10 adjacent each face of the web 48 of adjacent rails. While Fig. 1 illustrates only one shim, the shim on the opposite side is directly opposite the shim illustrated. The shim of Fig. 3 is not reversible so that two forms of shims are provided. These shims are identical in construction with the exception that the parts are so reversed as to bring corresponding parts in opposed relation when applied to the rails.

In Fig. 1, I illustrate the manner in which the shims are applied to the rails, at which time the bolt 44 in the position 50 is partly encircled by the curvature 52 of the shim. The shim is provided with a second curvature 54 which partly encircles the bolt 44 in the position 56. The curvatures 52 and 54 are of sufficient depth to easily accommodate the two bolts, but the curvatures co-operate with the bolts to prevent endwise movement of the shims. At the same time, the shims are cut

away at 58 and 60 to terminate slightly short of the rail ends, thus preventing overlapping relation with the rails 40 and 42, respectively. While the curvatures 52 and 54 permit slight endwise movement of the shim, the movement is not sufficient to shift the flanges 14 and 24 into overlapping relation with the rails 40 and 42, respectively.

In operation, the splice bars 18 have pressure relation with the faces 20 and 28 and are at all times spaced slightly from the webs 48. After placement of the shims and the splice bars 18, the bolts 44 are tightened. Such tightening of the bolts 44 draws the splice bars 18 into pressure relation with the flanges 14 and 24. As the bolts are tightened, the splice bars 18 are drawn home, at which time the flanges 14 and 24 are pressed between the splice bars and the rail head and base flange. In Fig. 1, I have illustrated the rail end 42 as being lifted slightly as at 62. At the same time, the rail end 40 is slightly lower than the other rail, but the upper surfaces lie substantially in the same plane. According to Fig. 1, the flanges 14 and 24 act as fillers, whereby proper pressure relation is again established between the splice bars 18 and the rail heads and flanges.

In the drawing I have illustrated one size of the shim, but in actual practice shims of different shimming value may be carried in stock so as to meet different repair conditions. The flanges 14, 24, 32 and 34 will be made up in different degrees of taper, but the length will vary slightly, depending upon the degree of taper. Relatively thin flanges or flanges having a slight degree of taper will be slightly shorter, but under all conditions, the flanges will be tapered to a feather edge. I have found that flanges varying in thickness from .03, .05 to .07 of an inch are sufficient to meet all practical requirements with the thinnest flanges made approximately one inch shorter than the longest. The length is calculated from the vertical center line of the shim as a whole.

Fig. 1 illustrates the manner in which my shim compensates wear with the load supporting face of the rail end 42 built up to the exact level of the rail end 40.

Without further elaboration, the foregoing will so fully explain my invention that others may, by applying current knowledge, readily adapt the same for use under various conditions of service.

I claim:

1. In a rail joint, the combination of rails each having a head and a base flange, splice bars cooperable on said heads and the base flanges for connecting the rails, a shim positioned between each splice bar and the rails, each shim having a tapered flange positioned between one splice bar and the head of one rail, each shim having a second tapered flange positioned between one splice bar and the base flange of the other rail, said flanges tapering in the direction of the ends of the shims, and bolts passing through the splice bars and the rails, each shim including a diagonal reach interconnecting the flanges of that shim, said diagonal reaches including shoulders spaced closely adjacent to bolts, to restrain the shim from endwise relative movement.

2. In a rail joint, the combination of rails each having a head and a base flange, splice bars cooperable on said heads and the base flanges for connecting the rails, a shim positioned between each splice bar and the rails, each shim having a flange positioned between one splice bar and the head of one rail, each shim having a second flange positioned between one splice bar and the base flange of the other rail, the first mentioned flange tapering in the direction of its free end, and bolts passing through the splice bars and the rails, each shim including a diagonal reach interconnecting the flanges of that shim, said diagonal reaches including shoulders spaced closely adjacent to bolts, to restrain the shim from endwise relative movement.

3. In a rail joint, the combination of rails each having a head and a base flange, splice bars cooperable on said heads and the base flanges for connecting the rails, a shim positioned between each splice bar and the rails, each shim having a flange positioned between one splice bar and the head of one rail, each shim having a second flange positioned between one splice bar and the base flange of the other rail, one of said flanges tapering in the direction of its free end, and bolts passing through the splice bars and the rails, each shim including a diagonal reach interconnecting the flanges of that shim, said diagonal reaches including shoulders spaced closely adjacent to bolts, to restrain the shim from endwise relative movement.

ELMER SCHUPPNER.
